UNITED STATES PATENT OFFICE.

JAY F. WILSEY, OF JERRY CITY, OHIO.

CHURN.

SPECIFICATION forming part of Letters Patent No. 433,503, dated August 5, 1890.

Application filed January 29, 1890. Serial No. 338,502. (No model.)

To all whom it may concern:

Be it known that I, JAY F. WILSEY, a citizen of the United States, residing at Jerry City, in the county of Wood and State of Ohio, 5 have invented certain new and useful Improvements in Churns; and I do hereby declare that the following is a full, clear, and exact description of the invention, which will enable others skilled in the art to which it applies to make and use the same, reference being had to the accompanying drawings, and to the letters of reference marked thereon, which form part of this specification.

My invention relates to churns of that character in which a series of revoluble dashers are caused to agitate the material to be churned.

The object of my invention is to provide a series of paddles or dashers set obliquely to 20 radial planes passing through the shaft, with the inclination of each dasher directed from the outer end of the churn toward the center, whereby to not only agitate the cream circumferentially of the axis of the dashers, but 25 longitudinally of the churn.

A further object is to introduce a current of atmospheric air into the churn in such relation to the axis of the dashers that they (the dashers) by their obliquity to the axis and 30 point of ingress of the air will draw the same into the churn and force the air into the cream.

A further object is to cause the air to enter at the desired points of ingress and escape by 35 a separate and distinct point of egress.

A further object is to journal the shaft upon which the dashers are secured in a manner to allow of easy removal of the same.

A further object is to so construct the air-ingress ports that they may be provided with 40 a removable foraminous covering, thereby preventing the ingress of dust or dirt particles incident to the draft of air through the ports caused by the vacuum created by the 45 obliquely-moving dashers.

The invention consists in the parts and combination of parts hereinafter described, and pointed out in the claim.

In the drawings, Figure 1 is a side elevation of a churn, showing the gearing for actuating the dashers in edge view. Fig. 2 is a 50 longitudinal vertical sectional view through

the center of the churn, showing the dasher-shaft and journals in full lines. Fig. 3 is a transverse section on lines xx , Fig. 1; and 55 Fig. 4 is a detail view of a section of the end of the framing of the churn, showing one of the air-ingress ports provided with the removable foraminous covering.

The receptacle for cream is formed of two 60 end pieces A and A', respectively, to which is secured the metal U-shaped body portion B, preferably by forming a correspondingly-shaped groove C in the end pieces and letting the ends of the body B therein, and drawing 65 the end sections closely against the ends of the body by means of rods D, extending longitudinally of the churn, the edges of the sides being bent around the upper rods, as shown in Fig. 3. The receptacle is mounted upon 70 legs F, secured to the end pieces and closed by a removable cover G, formed with an air-escape pipe H.

In each end piece A of the churn-body there is formed a vertical air-duct I, leading from 75 the top down to near the middle portion of the end piece. Communicating with this vertical air-duct near the top is an outer lateral opening J for admitting air from the outside, which opening is guarded against the 80 ingress of dust, &c., by a removable foraminous covering K, held in place by being secured to a frame which slides in ways K', attached to the end piece A, and at the bottom of the air-duct I there is an inner lateral 85 opening J' on a line with the upper surface of the dasher-shaft.

L designates the dasher-shaft, the body of which is formed of wood, upon each end of which is secured metal thimbles, one of which 90 L' is formed with a rectangular perforation in the end to receive the square end of a journal M, having a bearing in end piece A, upon which there is secured a pinion M', which meshes with a gear-wheel N, journaled 95 in the upper portion of the churn, and provided with a crank N'. The opposite end has a thimble L'' secured thereon, which has a semicircular recess into which is centered a bearing O, screw-threaded to run into a nut 100 O' set into head A', the end of the bearing O being provided with a thumb-hole by which to set the same to any desired adjustment—as a pivotal bearing—and being held to the ad-

justment by means of a nut P, run upon the same, and which bears upon the nut O' frictionally to prevent the bearing from unscrewing.

- 5 P' designates pins passed through shaft L at diametrically-opposite points, upon which are secured the dashers Q, one upon each end, the dashers being inclined oppositely and at oblique angles to a radial plane passing 10 through the shaft, whereby in the revolution of the shaft the outer ends of the dashers—*i.e.* those ends nearest the ends of the churn—have an inclination toward the center of the churn, thus causing the cream to be moved circumferentially of the axial plane of the shaft, and also longitudinally of the same, thereby 15 by pressure divesting the butter-globules of the membrane that incases them as the cream is urged to the center by the obliquity of the 20 dashers—an effect far superior to that caused by direct impact of the dashers.

An important result attained by locating the air-inlets J' on a line with the dasher-shaft and having one of these inlets at each 25 side is that, owing to the vacuum in the vicinity of these inlets caused by the revolution of the dashers, a constant current of air is drawn into the churn from each side, meeting in the middle along the line of the shaft, from which 30 position, as the fluid is urged toward the center, it is thoroughly distributed and incorporated into the cream, thereby, on a well-known principle, causing the butter-globules to readily separate from the cream, and also serving 35 to carry off the impurities of the latter.

In order to provide means for cleansing the air-ducts, the openings extend through the upper ends of the end sections, as shown, whereby when the cover G and the forami- 40 nous coverings K are removed water may be poured into the vertical passages I, which, find-

ing its egress into the churn, removes any butyric particles that may have been forced therein.

In order to remove the dasher-shaft, the nut 45 P is run back, thereby allowing the journal-bearing O to be unscrewed from contact with the bearing in thimble L'', when by inclining the shaft it can be withdrawn from the churn.

It will be understood from the foregoing description that by the agitation of the cream longitudinally in opposite directions, and also spirally, due to the obliquity of the dashers, the whole mass of cream is agitated evenly, 55 thereby converting the maximum amount into butter of a finer texture than when the operation is effected by direct impact, and that by reason of the obliquity of the dashers and the relative point of ingress of air there is insured a constant current of air in incorporation with the cream.

What I claim is—

In a churn having a horizontal dasher-shaft journaled therein, end section of the churn- 65 body having vertical air-ducts leading from the top downward toward the shaft, lateral air-passages leading from the outer side of the churn to said ducts and lateral air-passages leading from the bottom of the ducts 70 to the inner side of the churn, and a churn-cover closing the upper ends of the air-ducts and having an air-vent, for the purposes set forth.

In testimony that I claim the foregoing as 75 my own I hereby affix my signature in presence of two witnesses.

JAY F. WILSEY.
